(57) **CLAIM**

The ornamental design for a wearable medical injection device, as shown and described.

DESCRIPTION

FIG. 1 is an upper perspective view of a wearable medical injection device.

FIG. 2 is a front view of the wearable medical injection device of FIG. 1.

FIG. 3 is a rear view of the wearable medical injection device of Figure of 1.

FIG. 4 is a top view of the wearable medical injection device of FIG. 1.

FIG. 5 is a bottom view of the wearable medical injection device of FIG. 1; and,

FIG. 6 is a left view of the wearable medical injection device of FIG. 1, of which the right view is a mirror image.

The broken lines in the drawings illustrate portions of the wearable medical injection device and form no part of the claimed design.

1 Claim, 6 Drawing Sheets
